VULCANIZER

Filed July 29, 1929

UNITED STATES PATENT OFFICE

ROYAL G. DANIEL, OF DENVER, COLORADO

VULCANIZER

Application filed July 29, 1929. Serial No. 381,896.

This invention relates to vulcanizers, and more particularly to tire-vulcanizers of the type shown and described in my application for patent, Serial No. 323,760, filed on the 5 4th day of December, A. D. 1928.

In vulcanizers of this character, a flash boiler generates the heat necessary to vulcanize tire covers and tire tubes held upon the exterior surface of a table to which the 10 boiler is applied and it is an object of the present invention to provide the table with an upstanding back and to extend the steam space of the boiler into the back whereby to subject two sides of a tire held upon the 15 table, simultaneously to the vulcanizing heat.

Another object of the invention resides in the provision of a mounting whereby the tire-supporting table and flash boiler may 20 be readily adjusted with relation to a pressure screw which holds the tire in contact with the heated surfaces of the vulcanizer.

A further object is to provide a vulcanizer of the improved construction with conveniently located clamps for vulcanizing inner tubes, another object resides in an improvement in the construction of these clamps whereby they are held automatically in adjusted positions and still further objects reside in details of construction and 25 novel arrangements and combinations of parts as will be fully brought out in the course of the following description.

In the accompanying drawing in the several views of which like parts are similarly 30 designated,

Figure 1 represents a partially sectional side elevation of a vulcanizer made in accordance with the present invention,

Figure 2, a fragmentary section along the line 2—2, Figure 1,

Figure 3, a section taken on the line 3—3, Figure 1,

Figure 4, an end elevation of the vulcanizer looking in the direction of the arrow A in Figure 1,

Figure 5, a fragmentary end elevation of a vulcanizer of modified construction, and

Figure 6, an elevation looking in the direction of the arrow B in Figure 5.

In the construction shown in Figures 1 to 4 of the drawing, the vulcanizer comprises a stand or table 5 having at one side an upstanding back 6. The stand and the back are hollow to provide water and steam 55 spaces 7 and 8.

The space 7 of the stand is partially cylindrical as at 9, and in spaced relation to the wall of this cylindrical portion is a tubular housing 10 for an electric heating 60 element.

The heating element comprises a core 12 made of porcelain or other heat-resisting material, which is supported by heads 13 that close the ends of the housing, and a resistance coil 14 that is wound around the core, preferably in a circumferential helical groove thereof. Binding posts 15 on one of the heads, connect the resistance coil in an 65 electric circuit.

It is a distinctive feature of the invention that the water and steam spaces exteriorly of the housing of the heating element and coextensive with the top of the table and the back of the same, are restricted in width so as to spread the fluids within the same in sheets that are readily affected by the heat generated in the housing and readily transmit the heat to the surfaces of the table and the back used in the vulcanizing or curing operation.

The entire construction, as hereinabove described, comprises a flash boiler adapted for the instantaneous generation of heat during each actual operation which avoids the necessity of heating the vulcanizer beforehand and between operations, as is required in many vulcanizers at present in use.

The wall of the cylindrical portion of the water and steam space of the boiler is packed in a bed 16 of mineral wool or other insulating material that occupies the space of the hollow stand exteriorly of the water and steam space, and the rear surface of the back of the table may be protected from the cooling influence of the atmosphere by a covering of asbestos shown at 17.

It is to be understood that while the use of steam as a heating medium is preferred, any liquid or semi-liquid taking high tem- 100

peratures without vaporization, may be employed.

The stand or table is adjustably supported upon a base 17 by means of runners 18 of 5 dove-tail section, slidably fitted in correspondingly formed ways 19 of the base.

A standard 20 rising from the back of the base has an arm 20a projecting laterally therefrom over the back and the top of the 10 table, and this arm has at its end, a screw-threaded opening to receive the pressure screw 40 by means of which a tire 21 to be vulcanized, is held in position.

The screw 40 has at its lower end, a tire-engaging foot 22 connected with the screw by a ball-and-socket joint and it has at its 15 upper end, a hand-wheel 23.

The table top may be extended for vulcanizing inner tubes. The extensions projecting at opposite ends of the table have 20 been shown at 24, and at a side of the extensions are upright standards 25 for the support of the clamps by which the tire tubes are secured.

25 The clamps each consist of an arm 26 provided at one end with a sleeve 27 slidable upon the respective standard, and having at its other end a screw-threaded opening for the support of a screw 28 similar in construction to the pressure screw 40.

The screw 28 has at one end, a foot 29 connected with the screw by a universal joint to engage a tire tube placed upon the respective extension of the table and it has at its 35 upper end, a handle 30 to facilitate its manual rotation.

The standards 25 are serrated, corrugated or otherwise roughened to increase the frictional contact of the sleeves 27 of the relatively sliding arms 26.

In the operation of the vulcanizer, a mold 31 adapted to hold a tire cover, is placed upon the table top against the back 6, as shown in the drawings. The mold may be 45 locked in place by latches 32 pivotally secured at the ends of the back and cooperating with studs 33 on the corresponding ends of the mold.

After the tire cover has been placed in the 50 mold, a sand bag 34, or other flexible filler, is inserted in the cover and the cover is pressed into intimate contact with the mold by pressure exerted through the medium of the screw 40.

55 The circuit of the heating element is now closed and the heat imparted to the water in the flash boiler is quickly converted to steam which heats the table top and the upright back 6 and by these means heats the mold 31.

60 It has heretofore been necessary, in order to heat a side of the tire cover as well as the tread portion of the same, to place the mold first in the position in which its tread portion is opposite to the top of the table and 65 then in a position in which the side of the

mold corresponding with the side of the tire cover to be vulcanized, is in contact with the top of the table, or, as a variant, different kinds of molds were used, one to vulcanize the tread portion of the tire cover and one to vulcanize the side portion of the same. 70

By the use of the present invention but one mold is used, and when this mold is placed in contact with the heated table top and with the heated upright back of the same, both the tread portion and a side portion of the tire cover are vulcanized at one and the same time, without changing the position of the mold or without the use of 75 two or more molds. 80

The table or stand slidably mounted on the base, is easily adjusted to vary to position of the mold relative to the pressure foot.

The use of the pressure screws in curing inner tubes is obvious and requires no further explanation. 85

The sliding arms on the standards 25 are automatically locked in any adjusted position by the weight of the screws at the outer ends thereof and the roughened surface of the standards greatly aids in frictionally locking the arms in their adjusted positions. 90

In the modified construction illustrated in Figures 5 and 6, the back 35 is placed in the middle of the table so that two molds may be used at one and the same time to vulcanize two tire covers simultaneously. 95

The back and the stand are hollowed as before to provide the water and steam space and two heating elements are employed to generate the heat required for converting the water into steam. 100

The pressure screws for curing inner tubes are placed at the edges of the table top so that the latter may be used for vulcanizing inner tubes as well as tire covers. 105

The standard 36 for the arm on which the pressure screw 40 is supported, is in this construction, slidable on top of the wall by means of a runner 37 of dove-tail section on the standard, fitted in a corresponding groove 38 in an enlargement of the wall. 110

What I claim and desire to secure by Letters Patent is:

1. A vulcanizer comprising a stand provided with a top and a back above the top, and having interiorly a chamber including spaces in the top and the back, a heating element in the chamber and latches on the back for locking a mold placed on the stand, in a position in which it contacts with the top and the back. 120

2. A vulcanizer comprising a stand for the support of a tire mold, having a chamber inclusive of a space or spaces coextensive with a surface or surfaces engaged by the mold, a heating element in the chamber, a base upon which the stand is adjustably supported, and a pressure element on 125 130

- the base, disposed to act upon a tire in the mold.
3. A vulcanizer comprising a stand for the support of a tire mold, having a chamber inclusive of a space or spaces coextensive with a surface or surfaces engaged by the mold, a heating element in the chamber, a base upon which the stand is slidably supported, and a pressure element on the base, disposed to act upon a tire in the mold.
4. A vulcanizer comprising a stand having a top surface and a back surface at an angle to each other to be simultaneously engaged by a mold placed upon the stand, the stand having interiorly spaces of narrow width, coextensive with the said surfaces, an oblong chamber below the space along the top surface, and lengthwise parallel therewith, and a packing-space around the chamber, the chamber communicating with the spaces and being adapted to contain a heating-element, and a bed of insulating material for the chamber, within the packing-space.
5. A vulcanizer comprising a stand having a table-member and a back member, to engage with an object placed on the stand, and an extension of the table-member beyond an end of the back member, the stand having interiorly a narrow space coextensive with the outer surfaces of the members to heat the same by means of a heating fluid and pressure-elements cooperative, respectively, with the table-member and with the extension thereof.
6. A vulcanizer comprising a stand having exteriorly a horizontal surface and an upright surface back thereof, and, interiorly, narrow spaces coextensive with said surfaces, and a chamber connected with the spaces by a restricted passage and adapted to contain a heating-element, and a pressure-element cooperative with the horizontal surface.
7. A vulcanizer comprising a stand having interiorly a narrow space with a heat conductive wall, the outer surface of which is adapted to be engaged by an object placed on the stand, and, a chamber connected with the space by a restricted passage and adapted to contain a heating-element, a non-heated extension of the wall at an end of the stand, and pressure elements cooperating, respectively, with said surface and said extension.
8. A vulcanizer comprising a stand having a table-member and a back member, outer surfaces of which are at an angle to each other, to engage an object placed on the stand, the stand having interiorly narrow spaces coextensive with said surfaces, and the surface of the table member forward of the back member being flat and even to its opposite edge to admit of sliding an object on the said surface across its said opposite edge, and a pressure-element cooperative with the table-member.
9. A vulcanizer comprising a stand having a table-member and a back member, outer surfaces of which are at an angle to each other, to engage an object placed on the stand, the stand having interiorly narrow spaces coextensive with said surfaces, and the surface of the table member forward of the back member being flat and even to its opposite edge to admit of sliding an object on the said surface across its said opposite edge, an extension of the table-member beyond an end of the back member, and pressure-elements cooperating, respectively, with the table-member and with its extension.
10. A vulcanizer comprising a base, a movable stand member on the base having an outer surface to engage an object placed on the stand, and having interiorly a space coextensive with said surface, to heat the same by means of a heating-fluid, a standard fastened on the base and projecting over the stand-member in detached relation to the same and a pressure-element on the standard, cooperative with a surface of the stand.
11. A vulcanizer comprising a stand having substantially horizontal and vertical surfaces for heating a tire in vulcanizing same, the stand having an enclosed space below and behind said surfaces respectively, a heating element in said space, and pressure means cooperating with the surfaces.
12. A vulcanizer comprising a stand having substantially horizontal and vertical surfaces for heating a tire in vulcanizing same, the stand having connecting enclosed spaces below and behind said surfaces respectively, heating means in one of said spaces and disposed to heat the other, and a pressure element cooperative with a surface of the stand.
13. A vulcanizer comprising a stand having interiorly a narrow water-space with a heat-conducting wall for the transference of heat to an article engaging the wall exteriorly of the stand, and a tubular chamber adapted to contain a heating-element and communicating with the water-space by a restricted passage.
14. A vulcanizer comprising a stand having interiorly a narrow water-space with a heat-conducting wall for the transference of heat to an article engaging the wall exteriorly of the stand, a tubular container communicating with the water-space, and a housing closely spaced from the wall of the container, within the same, and adapted to contain a heating-element.
15. A vulcanizer comprising a stand having interiorly a narrow water-space with a heat-conducting wall for the transference of heat to an article engaging the wall exteriorly of the stand, an open-ended, tubu-

lar chamber communicating with the water-space, and closing means at the ends of the container adapted to support a heating-element in the chamber.

5 In testimony whereof I have affixed my signature.
